R. M. EVANS.
RAILWAY SWITCH.
APPLICATION FILED MAR. 7, 1917.

Patented Dec. 31, 1918.

UNITED STATES PATENT OFFICE.

ROBERT M. EVANS, OF SEATTLE, WASHINGTON.

RAILWAY-SWITCH.

1,289,713.

Specification of Letters Patent. Patented Dec. 31, 1918.

Application filed March 7, 1917. Serial No. 152,971.

To all whom it may concern:

Be it known that I, ROBERT M. EVANS, a citizen of the United States, residing at Seattle, in the county of King and State of Washington, have invented certain new and useful Improvements in Railway-Switches, of which the following is a specification.

This invention relates to improvements in railway switches; and its object is to provide a conveniently operable switch which is characterized by being automatically adjustable to accommodate traffic.

With switches hitherto in use, it has been necessary to provide large spaces in which to swing the switch tongues in order to afford room on both sides of the tongues for the flanges of car wheels traveling over the switch. These relatively large spaces are objectionable and oftentimes dangerous to passing vehicles and the hoofs of draft animals which become caught in such recesses between the rails and notably so in urban places.

Such danger and consequent cost due to the incurred damage is dispensed with by the present invention through the provision of switch tongues which are adapted to operate in small spaces and adjust themselves to the passage of trains without interfering with or endangering general traffic.

To these ends, I provide switch regulating devices comprising spring-pressed means for holding the heel-ends of switch tongues with coöperating devices whereby the tongues are shifted from their point ends, as will be hereinafter described and claimed.

In the accompanying drawings, Figure 1 is a plan view partly broken away, of a split switch embodying my invention. Fig. 2 is a transverse sectional view through 2—2 of Fig. 1. Fig. 3 is a transverse sectional view through 3—3 of Fig. 1, showing the switch-operating lever in a position it will occupy when the switch tongues are about to be shifted; and Fig. 4 is a sectional view through 4—4 of Fig. 3.

The reference numerals 5, 6 and 5¹, 6¹ represent the rails of the main track line; 7, 7¹ are the rails of a turn-out; 8, 8¹ are the usual guard rails, and 9, 9¹ are the switch tongues, as arranged for a split switch.

The upper or body portions of the switch tongues are formed with side faces 10 which extend from the respective points 11 to 55 knuckles 12, whence they are of advan-

geously uniform widths to the heel ends 13 of the respective tongues.

Integral with and extending outwardly from the body portions of the respective tongues are flange elements 14 which are 60 adapted to have their outer edges normally abut against the web elements 15 (Fig. 2) of the adjacent rails 5 and 7¹ through the agency of helical springs 16 for operating against the heads 17 of push rods 18 which 65 are connected to the respective tongues in proximity to the heels thereof. Provided for said springs and rods are casings 19 which are secured to a track-tie or other rigid support and the casing is provided 70 with a removable cover-plate 20, as shown in Fig. 2.

Adjacent to their points, said tongues are united by means of a connecting rod 21 and lengths of pipes 22 and 23 which respectively serve as distance pieces between the tongues and between each of the latter and nuts 24 engaging screw-threaded portions of the rod.

The pipes 22 between the tongues are desirably connected by an internally threaded coupling sleeve 22¹ engaging screw threads of the pipes, and which enables their effective lengths to be adjusted to regulate the distance between the tongue points. One 85 end of the connecting rod 21 is secured by means of nuts 25 to a frame 26 positioned within a stationary casing 27 at one side of the track.

This frame is in the nature of a plate 90 having two upturned extremities or walls 28 and 28¹. Slidable transversely of the track upon the central part of frame 26 and a guide 29, is a block 30 having adjustable rods 31 and 31¹ extending from its opposite ends and arranged to encounter the frame walls 28 and 28¹ when the block is moved in one transverse direction or the other.

To shift this block, I employ a lever 32 100 which is fulcrumed by a pin 33 which extends into a vertical slot 34 of the casing wall 27¹ and has a stud 35 engaging in a hole provided in the block.

By swinging the lever about the axis of 105 its fulcrum pin, the block is accordingly moved toward or from the track to correspondingly move the frame and thereby shift the switch tongues.

The rods 31 and 31¹ of the block are, how- 110

ever, adjusted in the block so that there will ensue lost motion to the block sufficient to enable the lever to be swung upwardly from its position in the casing 27 and beyond a vertical plane, as represented in Fig. 3, before a block pin, as 31¹ for example, encounters the adjacent wall 28¹ of the frame 26, whereupon the frame 26 is urged onward to throw the switch tongues during the downward movement of the lever accomplished by a push from the operator applied to the end of the lever.

To facilitate such movements of the lever and the parts which are influenced thereby, the lever is provided at its free end with a relatively heavy weight 32¹ and which is desirably slotted, as at 32² (Fig. 3), to receive the operator's fingers when raising the lever preparatory to encountering the load in throwing the switch tongues.

By having the fulcrum pin 33 movable in a vertical slot 34, it is brought into dead center positions with respect to the axis of the connecting rod 21 to lock the tongues in their two extreme positions.

In practice, the casing 27 has hingedly connected to one of its sides a cover plate 37 to close the casing when the lever is housed therein.

The operation of my improved switch devices may be explained as follows:

When a tongue is in the position of that indicated by 9 in Fig. 1, the face 10 thereof will bear against the bulb element of the track rail 5 while the flange 14 of the referred-to tongue will bear against the web element of the rail and in consequence of being thus juxtaposed with the rail, the tongue is positively held against any outward displacement.

The other tongue 9¹ has its point 11 bearing against the adjacent guard rail 8¹ while at its heel end it is yieldingly held by the associated spring 16 to have the tongue flange 14 bear against the web element of the rail 7¹. By reason of the shape of the tongue, there will be but a relatively small space, say one-fourth of an inch, at α between the central portion, approximately, of the tongue 8¹ and the rail 7¹ instead of a wide space, as in the older switch construc-

tion where the tongue point is required to be swung a considerable distance to afford clearance for wheel flanges throughout the length of the tongue.

When cars, however, travel over the switch in the direction of arrow γ , the flanges of the wheels entering the interstice α thrust the rails apart for the passage of the wheels.

What I claim, is—

1. In a railway switch, the combination with the switch-tongues, a casing at one side of the switch, and a shifting bar coupling said tongues and extending into said casing, of a movable frame rigidly secured to said bar within the casing and provided with two end walls, a block slidably mounted on said frame, rods adjustably secured to and extending from the ends of said block, and a lever fulcrumed to the casing and engaging the block to actuate the block to cause one or the other of said rods to encounter an end wall of the frame to impart motion to the latter for shifting the switch tongues. 75

2. In a railway switch, the combination with the switch-tongues, a shifting bar coupling said tongues, and a frame serving as an extension to said bar, said frame being provided with walls disposed in spaced relations to each other, of a lever, and means shiftable through the agency of said lever and engaging the frame by one of the walls thereof to effect the shifting of the switch-tongues during the latter portion of the 85 movement of the lever.

3. In a railway switch, the combination with the switch-tongues, a shifting bar coupling said tongues in proximity to their points, and a reciprocatory frame operatively connected to said bar, of a lever, adjustable means adapted to be influenced by said lever to act through the agency of said frame and the bar to effect the shifting of said switch-tongues. 90

Signed at Seattle, Washington, this 28th day of February, 1917.

R. M. EVANS.
